SURFACE ABRASIVE AND POLISHING
MACHINE

Vernon R. Pallas, Cortland, N. Y.

Application July 18, 1936, Serial No. 91,329

8 Claims. (Cl. 51—71)

The present invention broadly relates to the art of abrasive polishing and more particularly pertains to an improved two-stage surface finishing machine of the multiple head type that is especially adapted to impart a superior bright luster to oil tempered steel or other drawn wire, metallic rods or the like striplike articles in order to rectify surface imperfections and thereby enhance the quality and marketability of such mill products.

To this end, it is preferred to work with a plurality of either stationary or rotatable grinder head means that may each be equipped with one or more tape rolls, endless belts or the like abrasives serving to compactly store a supply of such grinding agency of either the same or a dissimilar grit. A common work piece may be threaded and tautly strung through a series of such tapes. When brought into operative tangential engagement with the work piece, the active cutting region for each of the respective tapes is preferably but not necessarily confined to a localized zone.

When so confined, a virgin tape portion may then be regularly advanced crosswise toward their respective tangential cutting zones by feed roller means to individually renew the abrasives as fast as they become substantially spent. A processing of this kind gradually loads and thereby keeps the interstices of each such localized cutting zone substantially filled with fine abraded metal particles which of themselves tend to impart a relatively bright polish to a treated metallic strand by a virtual burnishing effect without any pronounced scratch marks, even when the cutting is performed in the initial or heavy grinder stage of my machine. Such practice enables me to slowly feed the abrasive for hours at a time while continuously grinding a correspondingly long strand at a high productive rate without having to contend with a reduction in the initial cutting properties throughout the life of the several tapes, all of which maintains a uniformly finished wire product.

For instance, when undertaking to grind off the black oxidized surface of an oil tempered steel piano or the like alloy wire and thereupon polishing this initially abraded surface to a high degree of luster, the present process is most advantageously carried out in a series of successive steps by the use of multiple tape carrying heads in which the first and last head groups constitute segregated abrasive stages that are made to perform in a distinctive manner.

My improvements chiefly rely upon a relatively rapid rate of longitudinal work piece travel for an active abrasive effect so as to permit of treating

an extensive surface in a given time without requiring any reciprocal head movement, such stroking being inherently slow because of the accompanying high inertia forces. The provision for multiple heads allows the rate of longitudinal wire travel to be intensified in a direct ratio to the number of heads used and the aggregate width of the respective tapes employed, which in turn correspondingly augments the abrasive capacity of my machine. For the most economical rate of advance on part of my distributed tape supply, this may be held at a substantially fixed gross footage of virgin tape per unit length of processed wire, irrespective of the number of heads resorted to.

For reasons that will now be explained, any predominating cutting component of such abrasive agency as measured crosswise of a non-rotating treated wire, also assumes importance for present purposes since it to a considerable extent determines the character of surface polish.

Certain conventional machines resort to a pair of spaced abrasive wheels that bodily rotate around a retained wire surface while these non-yieldable wheels run at high peripheral speed in a direction crosswise of the wire axis. Such instrumentality is being commonly used to initially cut down the diametral size of a treated wire but the scraping action thereof is found to score and thereby leave the ground surface replete with rather pronounced scratch marks. These marks generally extend transversely of the wire axis and must subsequently be reduced in depth by further penetrative grinding before a really brilliant polish can be imparted to the finished product.

My penetrative grinding is preferably completed in an initial stage or primary cutting zone without need of any other preliminary abrasive treatment and consists in substituting a series of laterally yieldable tapes for the cited wheels. The combined action of manifold abrasive tapes is herein relied upon to gradually cut down the wire surface in smooth stepwise fashion, the number of heads collectively required for my first or heavy duty stage depending in part upon the depth of pits that need to be ground out of the treated wire. Such improved light cut treatment minimizes the forming of pronounced scratch marks and imparts to the wire an initially satinlike finish possessing a partial luster that is substantially devoid of such marks. Variations in original diametral wire size as drawn are also thereby reduced and the product prepared to receive a final finish in my polishing zone without need of additional penetrative grinding.

It may here be pointed out that for rapid re-

removal of the original wire coating, the most effective results are to be had when certain of my multiple heads rotate around a suspended wire at a speed sufficient to insure a substantially 5 round product free from flats. The preferred procedure is to advance the wire through the primary cutting zone so as to generate one or more helices around the wire surface whose lead pitch is of considerable length with respect to its diametral 10 size, that is to say the effective or predominating cutting direction of the abrasive zone is purposely inclined markedly with respect to the work piece axis. Coarse grit may be used for the heavier initial grinding operations and the resulting surface 15 generally possesses a limited degree of light reflection, although ground down to a virtually smooth finish of substantially uniform diametral size.

I have experimentally determined that when 20 such partially bright finish is as a final step, stroked lengthwise by the same abrasive grit instead of crosswise of the wire, the surface characteristic appears to undergo a decided change in reflective capacity and then readily assumes 25 the desired bright luster, particularly so in the case of a tempered steel wire. A similar characteristic change in treatment may be brought about in divers ways. As an instance, the same underlying principle may be embodied by setting 30 up a difference in speed rotation between the first and last head means of my machine. The materially slower rate of rotation given the delivery end of such head means serves to correspondingly extend the cited helical lead pitch and thereby 35 finally stroke the wire in a direction that is kept substantially parallel to its axial travel, such helical inclination being preferably held to an angle of less than ten degrees. The use of a primary cutting zone and a polishing zone each 40 moving helically about the work piece, provides for two predominating cutting directions that are distinctive in that they are respectively given a different inclination relative to the axis of the work piece. The more scratch marks that are 45 allowed to occur crosswise of the treated wire, the greater will be the need for a final stroking in a longitudinal direction to attain the sought for high degree of luster.

If desired, the polishing or last stage may also 50 comprise a plurality of non-rotating tapes that are angularly staggered about the work piece in operative tangential engagement with the entire surface perimeter. Either of such practices enhances and effects a marked improvement in the 55 surface finish, it having been found that the insignificant transverse scratch marks that may occur during my primary grinding operation, may for all practical purposes be wiped out by the cited subsequent polishing operation.

The object of my improvements is to devise 60 processing apparatus of the indicated character that shall be capable of rapidly and economically grinding an elongated work piece surface in smooth stepwise fashion and to highly polish the same in long lengths to a reasonably close finished size by the use of separate primary and secondary abrasive zones which while rotating about a longitudinally moved work piece are respectively made 65 to generate helices each having a different lead pitch; also to overcome certain operative difficulties and limitations heretofore encountered in effectively polishing such products.

A principal item of processing expense, resides 70 in the cost of abrasive and a further object of my invention is to utilize such material to the utmost

at the minimum of cost per unit of treated wire length. Embodied herein are other improved structural aspects designed to carry out the foregoing principles of operation, all of which features will hereinafter be set forth in detail.

Reference is had to the accompanying two sheets of drawings showing a specific embodiment of my invention, and in which drawings:

Fig. 1 illustrates a plan arrangement of my multiple head type of combined abrasive and 10 finishing machine, and Fig. 2 is an elevational view thereof.

Fig. 3 shows a horizontal cross-sectional view of the spindle head assembly along line 3—3, and Fig. 4 a transverse view along 4—4 of Fig. 2.

Fig. 5 represents an elevational end view of the Fig. 3 head assembly, and Fig. 6 is a modification thereof that may be kept symmetrical about the center line A—B.

Fig. 7 schematically depicts a plurality of stationary heads each provided with a slowly advanced tape that are angularly staggered around and collectively brought into tangential engagement with a common work piece.

Referring in detail to the Figs. 1 and 2 assembly, this particular type of machine embodies a main girderlike bed plate 10 having a supplementary framework 11 attached to the forward end thereof. Spacedly disposed crosswise of such bed plate, are one or more pairs of 30 axially aligned bearing pedestals such as 12 and 13 of which the contiguous bored end faces may be kept spaced apart for the reception of control and drive means.

Mounted between each such pair of cooperating 35 pedestals is a tubular spindle 14 having a tensioned wire or the like treated strand 55 continuously threaded therethrough as in Fig. 3. A flanged disclike head 15 may be applied to each spindle end, which respectively constitute a forward and a rearward grinder unit. It will be obvious that any desired multiple of such units may be similarly incorporated. It is the intent to provide for two cooperating groups thereof, each affording a considerable number of grinder 45 heads that may respectively be built up in a single or in separate machines having independent bed plates arranged to successively treat a common work piece.

A separate adjustable sleeve such as 16 or 17 50 may rotatably encircle the respective end regions of each spindle and the outer ends of such complementary sleeves may respectively terminate in a master spur gear such as 18 disposed concentrically about the spindle axis. The respective innermost sleeve ends may be kept spaced apart and interposed therebetween is a spindle drive gear 19. Each spindle may be horizontally mounted within and axially retained by mated ball bearings such as 20 which circumscribe the 60 respective sleeves as in Fig. 3.

Fixedly carried at each inner sleeve end is a driven gear 21. As embodied in the given exemplification, two parallelly disposed idler shafts 65 may extend between each pair of pedestals 12 and 13; one such countershaft designated 22 may be located directly beneath the spindle 14 and the other shaft 23 may be laterally offset as shown in Fig. 4. The complementary spur gears 24 and 25 may be fixedly mounted upon the offset 70 idler shaft 23 (see Fig. 3) and thereby cause both of the sleeves 16 and 17 to be rotated in unison by the sectionalized control shaft 26 through the idler gear 27 carried by the countershaft 22.

For present purposes, it is preferred to rotate 75

the successive spindles in a like direction; to this end, a sectionalized gear shaft 29 may be run lengthwise of the bed plate, said shaft being superimposed over the sectionalized control shaft 26. Said gear shaft may be provided with a clutchlike coupling 30 intermediate its length to afford a detachable rear shaft section 29A. The forward end of the gear shaft 29 is extended to receive the overhanging main drive pulley 31. Adjacent to this pulley is a pair of similarly sized spur gears 32 and 33 of which one is keyed to the gear shaft and the other secured to the control shaft section 26A to drive the respective forward shaft ends at approximately equal speeds. Said gear and control shafts may be alignedly mounted by a series of split pillow blocks such as 34A and 35A, or 34B and 35B. The drive gearing for each spindle unit may be similarly arranged between each such pair of pillow blocks to include an idler gear 36 as in Fig. 4. In addition, the split gear shaft 29 and the split control shaft 26 are herein each provided with separate reduction gearing respectively designated 31 and 38 by which the respective rear shaft sections may be given a materially different rotative speed relative to the forward section thereof.

Each spindle head 15 preferably carries its own supply of abrasive tape as stored upon duplicate rolls of which the grit may be modified in accordance with present needs. It is to be understood however, that while the illustrative spools carry a supply of tape thereon in convolute formation, my invention is not confined thereto since the same result may be had when the stored tape is compactly stacked in laid plaited or other multiple courses instead of a spiral configuration; an endless abrasive belt may also be resorted to, particularly so when its virgin abrasive is slowly fed to the work piece as fast as such belt becomes loaded or otherwise substantially spent.

In the particular roll type of tape feed disclosed in Figs. 3 and 5, the web plate or disc of each head may be journaled to receive a pair of driven roller trunnions or pintles 42 which are parallelly disposed with respect to the spindle axis. Each interiorly overhanging pintle end may be provided with a planet gear such as 43 while each opposite end is slidably embraced by a feed roller 44. The outer free end of each such roller may be equipped with a remountable feed gear 45. Cooperating with each such roller is a retractile idler mate 46.

A take-up spool 48 which also rotates bodily with the head 15, is located adjacent to each feed roller. Bearing frictionally against the outermost flange of the spool 48, is a disc gear 49 that meshes with the feed gear 45, said disc being yieldably pressed toward the spool flange by the spring 50. A pair of similar but gearless supply spools 51 may be symmetrically disposed upon the same disc face. The abrasive tapes 52 and 53 may be separately threaded over suitable guide means 54, thence directed to the axial center of the disc head in superimposed relation with the abrasive sides facing each other, and whereupon the respective tapes are interposed between their mated feed roller means 45 and 46 to be independently wound upon their respective take-up spools 48 in transferred roll formation. A pair of relatively retractile backing jaws such as 47 serve to retain the complementary tapes in fixed spaced relationship so as to definitely size the treated wire diameter. For any fixed spindle speed, the described feed devices provide for a

substantially uniform tape advance throughout the entire tape length. The intensity of cutting action of each tape may be individually regulated by its jaw adjustment.

The rotation of my positively actuated feed roller about its own axis is preferably kept extremely slow to establish a corresponding low rate of tape movement transversely of and toward the work piece. A comparatively fast tape movement in relation to the axial travel of the work piece, tends to cut predominating scratch marks that run crosswise of the work piece axis. Such initial defacement is difficult to wipe out by a subsequent non-penetrative polishing step while bringing the treated product to a state of brilliant luster. The hazard of product wastage is herein materially reduced by an inherently smooth grinding in my primary zone.

In my preferred practice, the linear wire travel is maintained to at least five hundred times faster than the corresponding mean rate at which the several tapes are advanced into their respective cutting zones. Any suitable means may be employed for imparting a progressive linear movement to the non-rotating work piece as it passes through my abrasive heads. As an instance, actuated conventional reels such as 56 and 57 may transfer a coil of wire from one reel to the other. A reversing ratchet mechanism such as 58 may be provided to change the direction of wire travel in the event it is desired to repeatedly run the treated product through my apparatus, in several rather than a single pass where any unusually heavy grinding is required.

Attention will now be directed to certain control devices for selectively changing the rate of tape feed from a centralized control point that may be located in the supplementary frame 11 (see Figs. 1 and 2). The control shaft sections 26 and 26A are shown split at 64. These abutting shaft ends may be coupled by a differential drive gear unit comprising a pair of oppositely disposed bevel gears 65 and 66 that are respectively keyed to a different shaft end and provided with one or more idler gears therebetween as carried by the yoke member 68.

A main worm 69 is mounted forwardly of the yoke hub to engage a cooperating worm gear 70 carried upon the cross-shaft 71 and which shaft may be equipped with a supplementary reduction worm 72. Angularly superimposed upon the last named worm, is a lay shaft 73 that runs parallel to the control shaft 26A. Said lay shaft carries a supplementary worm gear 74 and also a driven or change gear 75. A mated driven change gear 76 may be mounted around the yoke hub to finally mesh with the gear 75.

The intent of such control gearing is to slightly alter the rotative speeds of the sectionalized shafts 26 and 26A. The speed of the forward shaft end 26A is fixed by the spur gears 32 and 33 which at the same time rotate the worm 69. Because of the well known planetary principle involved, the intermediate shaft section 26 may be made to run at somewhat faster or slower speed relative to the companion section 26A, that is fixed by the direction of rotation given to the yoke 68.

Referring further to Fig. 5, it will be seen that the grinder head there shown rotates in a counter-clockwise direction while the planet gear 43 may be made to rotate in a like or reverse direction, depending upon the differential speed ratio prevailing between the split shaft sections 29 and 29A. Said planet gear may be given

5 a diametral size identical with the master spur gear 18 upon which it rolls. Hence assuming the differential yoke 68 to be held stationary to impart the same speed to both control shaft sections, the grinder head 15 of Fig. 4 will then advance through an angle marked "A". Accordingly, the master gear will advance to exactly the same extent, with the result that no effective rotation will be imparted to the planet 10 gears 43 about their respective roller pintles.

15 On the other hand, if the master sleeve gear 18 were to be held stationary with respect to the revolving head 15, then the planet gear 43 would revolve at a comparatively faster rate and thus bring about a corresponding feed in abrasive tape from the respective supply spools 51.

20 By running the control shaft 26 at a speed slightly slower than its coupled shaft section 26A, the tape may be selectively fed crosswise of the work piece 55 at an extremely slow rate of advance. For different kinds of treated products, it is preferred to maintain a definite predetermined rate of tape feed that is kept proportionate to the rate of work piece travel.

25 The forward or rightward group of heads shown in Figs. 1 and 2 are intended to perform the primary grinding operations and as such, their respective tapes are preferably advanced somewhat faster than in the rearward or leftward

30 group of heads through which the polishing operations are completed. Because of the relatively heavy, stepwise grinding which the primary zone is ordinarily called upon to deliver, it is expedient to provide a larger series of grinder heads

35 for such primary zone than are comprised in the polishing zone. It is also preferred to run the lesser series of heads in the polishing zone at a comparatively slower rotation than those of the primary zone by the use of the reduction gears

40 37. The reduction spur gears 38 serve to correspondingly slow down the rear control shaft section 26B. The gears 38 may be replaced by a shiftable gear box providing for an adjustable speed ratio of wider magnitude.

45 By releasing the clutchlike coupling 30, the rear group of grinder heads comprised in the polishing zone, may be kept at rest without imparting any rotation thereto. When standing idle, the number of opposed tape pairs of such

50 polishing heads are preferably multiplied sufficiently and fixedly staggered so as to embrace the entire perimeter of the work piece in the Fig. 7 manner. It will be apparent from the foregoing description, that the mated tapes such as 55 52' and 52'', 53' and 53'', etc. for the respective heads are still advanced regularly but slowly toward the treated work piece while the latter is being dragged longitudinally onward between the reels 56 and 57. By resort to similar control

60 devices (not shown) all heads in both the primary and the polishing zones may be kept stationary by suitable retaining means.

65 The grinder heads in the primary zone may be supplied with virgin tape of relatively coarse grit while the finishing zone may utilize a finer grit or partially spent tape that has previously served in the primary stage. In certain instances, a mere cloth or metal tape or the like buffering or burnishing strip possessing little or no substantial abrasive property may be substituted in the polishing zone, in which event the corresponding rate of advance on part of such rubbing element is to be kept proportionate to requirements.

70 If desired, my machine may be simplified by 75 eliminating the spindle sleeves 16 and 17 and

substituting independent reduction worm gears or a suitable ratchet mechanism adapted to individually feed the several tape roller means without resort to centralized control for changing the rate of tape advance.

5 A further alternative is shown in Fig. 6 in that an endless belt 80 is utilized in lieu of a roll of tape. The feed mechanism for advancing such belt may be substantially identical with the Fig. 5 disclosure and in which the feed roller 44 corresponds in purpose to a positively driven belt pulley. In order to avoid cutting pronounced scratch marks crosswise of the work piece axis, it is preferred not to run such abrasive belt at high speeds. The use of an open belt of short 10 span requires frequent renewals in comparison to the more compact roll form of abrasive tape, which latter serves to maintain the cutting properties thereof over a protracted operating period without any shut down for tape replacement. In 15 addition, the cost of making endless belts and putting them in place tends to materially augment the abrasive cost per foot of polished product.

20 To recapitulate, it is important for present purposes that the initial grinding step be so conducted as to minimize the penetrative cutting of any pronounced scratch marks in said primary zone, all of which is most expeditiously carried out in stepwise grinding by the use of multiple 25 tapes. It is however within the scope of my invention to initially prepare the work piece by any equivalent grinding means so that no further penetrative grinding will be needed to bring such 30 virtually smooth surface to a higher degree of 35 luster by means of a separate polishing zone.

35 The last named zone may comprise a plurality of slowly rotating or stationary abrasive carrying heads adapted to finally stroke the work piece 40 axially in a wiping direction having an insignificant cutting inclination with respect to said axis, preferably less than ten degrees. Similar results may be had by superficially treating a wire or the like by a two stage process in which all grinder heads are held stationary and in 45 which the abrasive capacity of the primary zone is materially intensified with respect to that of the finishing zone. The respective staggered tapes comprised in each successive zone are then 50 regularly advanced crosswise of and toward the work piece. However, unless an abnormally large number of staggered tapes are resorted to in the Fig. 7 manner, (or a double or triple series thereof are disposed in tandem) to comprise the initial 55 or primary stage, the combined tape cutting capacity may prove insufficient to remove the required metal quota and to keep the treated article 60 free from flats at the herein contemplated fast linear travel of the work piece.

65 In an all stationary head assembly of this kind, the rate of tape advance into the primary zone may be kept different from that of the polishing zone so as to crowd the tape cutting action in the primary zone, but in both instances it is preferred to limit such tape feed and cause the work piece to travel longitudinally onward faster than the mean rate of tape advance. Such relatively slow tape feed prevents the final cutting of any pronounced scratch marks in the polishing zone that extend crosswise rather than lengthwise of a treated wire.

70 I have found that the attainment of a high class piano wire luster to present a difficult problem unless the processing steps are performed in proper sequence to include a preparatory step 75

that adequately smooths up the wire for a subsequent non-penetrative polishing operation. For instance, certain tests were conducted with my machine upon black coated piano wire in which the helical lead pitch in both the primary and secondary zones were kept identical and relatively short in length. While the wire was thereby ground to a smooth truly round diametral size and possessed a moderately bright finish, no high grade luster was imparted such as could readily be attained when the heads comprised in the polishing stage were rotated at a relatively much slower speed or were held stationary.

By simultaneously treating a wire as it is being fed continuously onward from the first through the second stage of my improved grinding apparatus, a relatively high rate of production may be maintained, all without need for duplicate handling or the accumulation of partially treated products awaiting a polish finish.

In case of a work piece of cylindrical profile when ground helically by the use of a localized tangential cutting zone in the manner herein contemplated, a change in the cross feed rate of the abrasive toward the work piece is not in itself sufficient to bring about a change in inclination of the resultant grinding action; instead the two controlling components thereof that fix such slope are herein centered in the rate of head rotation in relation to the longitudinal travel of the work piece.

It is thought the foregoing rather explicit disclosure will make evident to those skilled in this art the distinctive mode of treatment that is required to attain the polishing results herein contemplated. Furthermore, as used in the claims, the term "head means" is intended to be broadly directed to any housing means either rotary or stationary adapted to incorporate suitable abrasives together with associated feed mechanism, it being understood that I reserve the right to modify any other of my illustrative embodiments, all without departing from the spirit and scope of my invention, heretofore described and more particularly pointed out in the appended claims.

I claim:

1. In a surface finishing apparatus, the combination of a primary zone and a finishing zone that are adapted to cooperatively treat a common elongated work piece, said primary zone comprising a series of stationary head means each including a supply of abrasive tape that are collectively brought into operative tangential engagement about the work piece in angularly staggered relationship to embrace substantially the whole of the work piece profile, actuating means for advancing the respective tapes toward said work piece at a rate sufficient to bring about a penetrative grinding in stepwise stages and thereby impart a substantially smooth superficial finish to the work piece, and which polishing zone comprises a number of similarly disposed stationary head means in series of which the actuated abrasive tapes are collectively advanced to bring about a less intensive grinding rate to refine such initially finished surface and brighten the luster thereof, and means for longitudinally passing the work piece surface through the respective zones for successive treatment therein.

2. In a surface finishing apparatus, the combination of a primary zone and a finishing zone that are adapted to cooperatively treat a common elongated work piece, said primary zone comprising a series of stationary head means each including a supply of abrasive tape that are collectively

brought into operative tangential engagement about the work piece in angularly staggered relationship to embrace substantially the whole of the work piece profile, actuating means for advancing the respective tapes toward said work piece at a rate sufficient to bring about a penetrative grinding in stepwise stages and thereby impart a substantially smooth superficial finish to the work piece, and which polishing zone comprises a number of similarly disposed stationary head means in series including actuated feed means for advancing the respective tapes thereof independently of the tapes in the primary zone to refine the aforesaid smooth superficial finish and brighten the luster thereof, and means for longitudinally moving the work piece surface through the respective zones for successive treatment therein at a rate of travel not less than five hundred times faster than the mean rate of advance of the respective tapes comprised in such polishing zone.

3. In a surface finishing apparatus adapted to treat metallic wire, said apparatus comprising a series of rotatably mounted tubular head means having wire movably suspended therethrough with each component head provided with abrasive tape means respectively distributed in angularly staggered relationship about the wire axis to embracingly surround the major profile portion of said wire, actuated feed means advancing said tape means into operative engagement with the wire surface, drive means rotating the head means at successively different speed rates, and means moving the embraced wire longitudinally while the head means are being operated at a comparatively fast rotative rate in relation to the corresponding wire travel rate to generate a helically continuous initial grinding about said surface in a direction inclined with respect to the wire axis at an angle materially greater than ten degrees, and means for controlling the operation of the head means to cause the abrasive tape means thereof to superficially polish the initially ground wire in a direction inclined to the wire axis at less than eleven degrees.

4. A surface finishing machine comprising complementary grinder head means adapted to cooperatively treat an elongated work piece of annular profile while the work piece is being moved longitudinally, one such head means including penetrative abrasive means that are rotatably mounted and driven to maintain operative tangential engagement with the work piece surface and thereby constitute a primary zone which upon being rotated around said surface generates a helical grinding action of which the predominating cutting direction is inclined with respect to the axis of said work piece, and the other of which head means are non-rotatably mounted and provided with abrasive tape means also maintained in operative tangential engagement with the aforesaid surface to constitute a finishing zone, actuated feed means advancing said tape means crosswise of and toward the last named zone at a materially slower rate of advance than the corresponding crosswise rate given to the abrasive means of the primary zone and thereby imparting a final cutting direction that runs predominately lengthwise of the work piece axis, and means for longitudinally moving the work piece surface through the respective zones for successive treatment therein.

5. A surface finishing machine comprising a plurality of head means adapted to treat an elongated work piece, abrasive means carried by cer-

- tain of such head means and which certain heads are rotatably mounted and driven to maintain the abrasive means in operative tangential engagement with the work piece surface to establish a primary cutting zone wherein said surface is penetratively treated without producing flats, and the remaining of which head means are held stationary and each provided with abrasive tape means that are also brought into operative engagement with the aforesaid surface to constitute a polishing zone, means for longitudinally moving the work piece through said zones for successive treatment, and actuated feed means advancing the respective tape means of the polishing zone crosswise to the work piece at a rate slower than said longitudinal movement imparted to the work piece.
6. A surface finishing apparatus comprising a plurality of head means adapted to treat a metallic wire, abrasive means carried by certain of such head means and which certain heads are rotatably mounted and driven to maintain the abrasive means in operative tangential engagement with said wire and thereby establish a primary cutting zone wherein the wire surface is penetratively treated without producing flats, the remaining of which head means are each provided with abrasive tape means brought into operative engagement with the aforesaid wire surface to constitute a polishing zone, means for moving the wire longitudinally through said primary and polishing zones for successive treatment therein, means for controlling the operation of the remaining head means to cause the respective abrasive tape means thereof to polish the wire surface in a direction inclined with re-
- 5
- 10
- 15
- 20
- 25
- 30
- 35

spect to the wire axis at an angle materially less than ten degrees, and actuated feed means advancing the respective tape means of the polishing zone across the wire axis at a rate slower than the longitudinal movement imparted to the wire 5 while being treated in said polishing zone.

7. In a surface finishing apparatus adapted to treat an elongated work piece, stationary mounting means comprising a plurality of abrasive tapes and which tapes are collectively brought 10 into operative tangential engagement about the work piece in angularly staggered relation to constitute a cutting zone that embraces substantially the whole of the work piece profile, actuating means advancing the respective tapes to 15 toward such cutting zone, and means moving the work piece surface longitudinally through said zone.

8. In a unitary surface finishing machine, a pair of rotatably mounted tubular head means 20 adapted to have a reelable work piece entered therethrough, abrasive means carried by each such head means and which abrasive means operatively engage said work piece, drive means imparting a different rotative speed to the respective heads, means feeding the several abrasive means to the work piece, complementary reels respectively having said pair of head means interposed therebetween and being alternately arranged as supply and take-up reels with opposite work piece ends wound thereon, means for reversibly actuating the respective reels about the axis thereof to selectively drag the work piece through the aforesaid heads in opposite directions. 25

VERNON R. PALLAS. 30

35
